US0D1042803S

(12) **United States Design Patent** (10) **Patent No.:** **US D1,042,803 S**
(45) **Date of Patent:** **** Sep. 17, 2024**

(54) **AUTOINJECTOR HOUSING**

(71) Applicant: **Alvotech HF**, Reykjavik (IS)

(72) Inventors: **Elin Edwald**, Reykjavik (IS); **Hildur Zoega**, Reykjavik (IS)

(73) Assignee: **Alvotech HF**, Reykjavik (IS)

(**) Term: **15 Years**

(21) Appl. No.: **29/821,710**

(22) Filed: **Dec. 31, 2021**

(51) LOC (14) Cl. **24-02**

(52) U.S. Cl.

USPC **D24/113**

(57) **CLAIM**

The ornamental design for an autoinjector housing, as shown and described.

DESCRIPTION

FIG. 1 is a perspective view of an autoinjector housing, without a cap, showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

1 Claim, 3 Drawing Sheets
